US00D628167S

(12) **United States Design Patent**
Lai et al.

(10) **Patent No.:** **US D628,167 S**
(45) **Date of Patent:** **** Nov. 30, 2010**

(54) **LED**

(75) Inventors: **Chih-Ming Lai**, Miao-Li Hsien (TW);
Ming-Young Shiao, Miao-Li Hsien (TW)

(73) Assignee: **Foxsemicon Integrated Technology, Inc.**, Chu-Nan, Miao-Li Hsien (TW)

(**) Term: **14 Years**

(21) Appl. No.: **29/359,855**

(22) Filed: **Apr. 16, 2010**

(30) **Foreign Application Priority Data**

Feb. 1, 2010 (CN) 2010 3 0302902

(51) **LOC (9) Cl.** **13-03**

(52) **U.S. Cl.** **D13/180**

(58) **Field of Classification Search** D13/180;
D26/2; D5/2, 6, 51, 60, 61, 63; D20/22,
D20/28; D25/153, 155, 157; 257/79, 80,
257/81, 88, 89, 95, 98, 99, 100, E33.058;
313/483, 498, 500; 362/555, 800

See application file for complete search history.

(57) **CLAIM**

The ornamental design for an LED, as shown and described.

DESCRIPTION

FIG. 1 is a perspective view of an LED in accordance with a first embodiment of our new design.

FIG. 2 is a front elevational view of FIG. 1.

FIG. 3 is a rear elevational view of FIG. 1.

FIG. 4 is a left-side, elevational view of FIG. 1.

FIG. 5 is a right-side, elevational view of FIG. 1.

FIG. 6 is a top plan view of FIG. 1.

FIG. 7 is a bottom plan view of FIG. 1.

FIG. 8 is a perspective view of an LED in accordance with a second embodiment of our new design.

FIG. 9 is a front elevational view of FIG. 8.

FIG. 10 is a rear elevational view of FIG. 8.

FIG. 11 is a left-side, elevational view of FIG. 8.

FIG. 12 is a right-side, elevational view of FIG. 8.

FIG. 13 is a top plan view of FIG. 8; and,

FIG. 14 is a bottom plan view of FIG. 8.

The broken line showing of the environment is for illustrative purpose only and forms no part of the claimed design.
